FIRE ALARM SYSTEM

Olof Ingemar Harald Ekman, Stockholm, Sweden,
assignor to Telefonaktiebolaget L. M. Ericsson,
Stockholm, Sweden, a company of Sweden

Application May 19, 1931, Serial No. 538,568
In Sweden May 7, 1930

4 Claims. (Cl. 177—355)

In modern automatic fire alarm systems closed circuit current is used in order that the plant shall be under permanent control, said current passing through electric circuits containing heat sensitive switches or thermostats disposed at different places in the localities to be protected against fire and adapted, when heated, to interrupt said closed circuit current thereby causing an alarm device to be released. In order that a simple conductor breakage shall not wrongly produce a fire alarm signal it is now customary to arrange the system in such a way that the circuits or loops extending through the localities to be protected and including the thermostats are made with double or multiple conductors and provided with such relay means that an alarm signal is produced only when a line interruption occurs simultaneously in all conductors in such a double or multiple loop. Hitherto the different loops have been parallel-connected with each other which arrangement leads to an unnecessarily high closed circuit current consumption with consequent extra costs for loading a storage battery etc.

The present invention has for its object to bring about a simple and inexpensive but nevertheless reliable automatic fire alarm system with two or more conductors in the loops containing the thermostats and is substantially characterized by that the conductors in each individual loop are permanently connected in parallel whereas the different loops are connected in series with each other and connected to a relay means which is common to all the loops and adapted to selectively indicate an interruption in a loop conductor or a short circuit between the loop conductors and to produce an alarm signal only upon an interruption in all of said conductors occurring, the loops being also provided with a section indicating device adapted to mark the loop in which an interruption in a single conductor or an interruption in all conductors has occurred.

The invention will be more closely described with reference to the accompanying drawings. Figure 1 is a circuit diagram for an automatic fire alarm plant according to the invention with section relays (double wound) common to the two loop conductors in a loop for marking the section or loop in which an interruption or a short circuit has occurred. Figure 2 shows another embodiment with separate section relays which at the same time serve as auxiliary relays for producing a fire alarm signal. Figure 3 shows a modification of the arrangement according to Figure 1 with normally disconnected section relays

which are connected into circuit with time lag and also serve as auxiliary relays for producing fire alarm signals.

In Figure 1, I and II designate two series-connected loops or sections each consisting of two permanently parallel-connected conductors *a*, *b*, said loops or sections including a plurality of double thermostats *T* adapted to fuse in the event of a fire and to then simultaneously bring about an interruption in the loop conductors *a*, *b*. Said loops are in known manner extending through the localities to be protected against fire whereas the portion of the plant indicated under the horizontal dot and dash line is disposed on a central switch board in the building. Only two loops are shown but several loops may be connected in series in an analogous manner. *B* is the central battery which on account of the small current consumption in a plant according to the invention may consist of a dry battery, whereas in hitherto known plants it has been necessary to use storage batteries with expensive charging devices on account of the high closed circuit current consumption. Between the poles of the battery *B* the parallel conductors *a* and *b* are included in a main circuit which in each of the parallel branches formed by said conductors includes a control relay and a resistance. Thus a low resistance *M_a* and a control relay *R_a* having a high resistance are included in the *a*-conductor whereas a high resistance *M_b* and a control relay *R_b* are included in the *b*-conductor. The control relays *R_a* and *R_b* are normally passed by closed circuit current, then holding their contacts broken, whereas upon an interruption occurring in the corresponding loop conductor the appertaining control relay is de-energized, then closing its contacts. Shunted between the ends of the *a*- and *b*-branches in the respective loops or sections are the section relays *SR_I*, *SR_{II}*, each of said relays being provided with two windings on a common iron core and a common contact. In said relays the coils designated *a_I* and *a_{II}* are shunted between the ends of the *a*-conductors in the loops I and II respectively whereas the coils *b_I* and *b_{II}* are shunted to the corresponding *b*-conductor. When passed by current each of the windings *a_I*, *a_{II}*, *b_I*, *b_{II}* produces a magnet field sufficiently strong to alone attract the corresponding armature, and the two windings on a certain relay, by way of example *a_I*, *b_I* of the relay *SR_I*, are wound in such a way that they co-operate when simultaneously passed by current. *BRR* is an alarm-box control relay which is normally energized by the closed circuit current

and serves to indicate that the circuit for the electric release of the alarm-box magnet BM is not broken and that the clock-work in the alarm-box is wound up, a mechanically controlled contact k_3 in the alarm-box being opened when said clock-work is run down. FR is a fault relay common to the whole system which relay when energized in known manner connects a bell or an optical fault signalling device (not shown) into circuit.

The described arrangement operates in the following manner. Upon an interruption occurring in only one loop conductor, say the a -conductor of the loop I, the corresponding control relay R_a is de-energized at the normally closed circuit from the minus pole of the battery through the relay R_a the loops a of section I and II resistance M_a plus pole of the battery is broken, and releases its armature whereby its contact K_4 is closed. This has, however, no effect on the alarm-box magnet BM as the circuit for said magnet is broken at the contact k_2 of the other control relay R_b connected in series with the contact k_1 . As the short-circuit of the winding a_1 of the section relay SR_I normally caused by the a -conductor in the loop I is removed on account of the interruption said section relay is energized over a circuit traced as follows: From minus pole of the battery over contact K_4 of the relay R_a the upper winding of the relay SR_I the loop a of the section II resistance M_a , plus pole of the battery. The relay SR_I therefore closes its contact k_6 whereby the section lamp SL_I is lit and the fault relay FR energized, thereby marking the fault.

Each of the control relays R_a and R_b is provided with a contact k_4 which short-circuits the relay winding when the relay drops its armature whereby the current through the windings of the section relays SR_I and SR_{II} becomes stronger than otherwise would be the case.

Upon a simultaneous interruption in both the a - and b -conductors, which occurs practically only at the event of a fire, both control relays R_a , which is normally energized over the above-mentioned circuit, and R_b , which is normally energized over a circuit from the minus pole of the battery through resistance M_b over conductor b in sections I and II, winding of relay R_b to plus pole of the battery, drop their armatures, the contacts k_1 and k_2 being then simultaneously closed and the battery B connected directly to the alarm-box magnet releasing the same so that an alarm signal is produced. The said circuit is traced as follows: From the minus pole of the battery over contact K_1 of the relay R_a , over contact K_2 of the relay R_b , over contact K_3 of the alarm box magnet, through the winding of said magnet to the plus pole of the battery. Normally the battery is connected to the alarm-box magnet BM over the alarm-box control relay BRR having a high resistance, but the weak closed circuit current then occurring is not sufficiently strong to release the magnet BM. When the contacts k_1 and k_2 are closed said relay BRR is shunted whereby full current strength is obtained through the alarm-box magnet BM, which is then released as mentioned above. If, for example, the interruptions are located in the section I both windings a_1 , b_1 of the section relay SR_I will become energized and co-operate to attract the armature of the relay whereby the section lamp SL_I is lit indicating that the release of the alarm magnet has been caused by an interruption in said section.

If a short-circuit should occur between the a - and b -conductors of a loop the control relay R_a will still remain energized for the reason that it is connected in parallel with the high resistance M_b so that a sufficiently high voltage drop exists between the ends of the winding of said relay. The control relay R_b , which is parallel-connected with the low-ohmic current limiting resistance M_a , will, on the other hand, be de-energized, its contact k_5 being then closed causing a current to pass through the fault relay FR over a circuit from the minus pole of the battery through the winding of the relay FR, the low ohmic resistance r , the contact K_5 of the relay R_b to the plus pole of the battery. The relay FR attracts its armature and marks the fault. The section relays SR_I and SR_{II} still remain short-circuited by the loop conductors and consequently do not operate. If, when the fault relay FR attracts its armature, the section lamp SL_I or SL_{II} is not lit this is an indication that the marked fault is a short-circuit and not a conductor interruption. The section relays SR_I and SR_{II} which, as already mentioned, upon an interruption occurring are series connected with the control relays R_a and R_b should have high resistances as compared with the resistances of the latter relays in order considerably to reduce the voltages on the same so that the relays R_a and R_b positively drop their armatures and remain with their armatures released.

The arrangement shown in Figure 2 differs from the one shown in Figure 1 partially therein that the section relays are divided on two relays SR_{Ia} , SR_{Ib} and SR_{IIa} , SR_{IIb} respectively corresponding to the four simple windings a_1 , b_1 , a_{II} , b_{II} in Figure 1. Further, double fault relays FR_{Ia} and FR_{IIb} each having a group of signal lamps SL_a and SL_b are provided, one group for the a -conductors and one for the b -conductors. In addition to the ordinary contacts k_6 for lighting the signal lamps and magnetizing the fault relays the section relays are also provided with extra contacts k_7 and k_8 which are series-connected within each couple of relays SR_{Ia} , SR_{Ib} and SR_{IIa} , SR_{IIb} respectively appertaining to a section.

The arrangements according to Figure 1 is further attended by the inconvenience that the section relays are always connected into circuit. At a possible short-circuit within the coils of said relays the closed circuit current for the control relays R_a , R_b will remain closed over the short-circuited windings of the section relays even if a double interruption in the loops exists wherefore such a short circuit makes the fire alarm system inoperative. Said inconvenience is eliminated when using the system shown in Figure 2 in which the section relays SR_{Ia} , SR_{Ib} , SR_{IIa} and SR_{IIb} are normally disconnected and connected into circuit first after the corresponding control relays R_a or R_b have been de-energized and the corresponding fault relay FR_{Ia} or FR_{IIb} has operated.

In the two parallel main circuits leading from the two poles of the battery B through the a - and b -conductors in Figure 2 only the two control relays R_a and R_b and the resistances M_a and M_b are included. Besides being provided with the ordinary contacts k_6 for short-circuiting the relay windings when the relays are de-energized and with the series-connected contacts k_7 and k_8 for producing a fire alarm signal (by means of the alarm-box magnet BM) the relays R_a and R_b are each provided with an extra contact k_9 adapted

to close the current through the appertaining fault relay FR_a or FR_b respectively when the control relay drops its armature (upon a single or a double line interruption or a short circuit occurring).

Each of said fault relays FR_a and FR_b is provided with a contact k_{10} for closing the circuit of a fault indicating device indicated on the drawing as a bell KL , and also with an extra contact 10 k_{1a} , k_{11a} or k_{1b} , k_{11b} respectively for each section. Each of the last mentioned contacts is included in the circuit of the corresponding section relay SR_{1a} , SR_{11a} etc. having the same index. All section relays are thus normally disconnected 15 and are connected into circuit first after a corresponding control relay R_a or R_b has been de-energized and has connected the appertaining fault relay FR_a or FR_b into circuit, at the contacts k_{1a} , k_{1b} etc. of which relay the circuits for 20 the section relays are then closed. The section relays are as already mentioned provided with contacts k_6 for lighting the signalling lamps SL_a and SL_b and also with series-connected contacts k_7 and k_8 for auxiliary release of the alarm-box 25 magnet BM in case the contacts k_1 and k_2 should fail, for instance not be clean or stick.

The plant according to Figure 2 operates safely also in case a short-circuit in the windings of the section relays should occur. In said embodiment 30 the loops are normally included in lines which only contain the control relays R_a and R_b , the battery B and the resistances M_a and M_b but no other relay windings or resistances, which ensures that a closed circuit current strength the control relays R_a , R_b will actually be broken upon 35 an interruption in a loop conductor occurring and not maintained over any path of leakage. The control relays R_a and R_b thereupon connect the fault relays FR_a and FR_b into circuit while 40 simultaneously releasing the alarm-box magnet BM in case a double interruption has occurred, the fault relay FR_a and FR_b finally connecting the section relays SR_{1a} , SR_{1b} etc. into circuit. Said relays being thus energized with time lag in 45 relation to the control relays R_a and R_b first after the latter have performed their alarm function. Possible short circuits in the section relays therefore cannot prevent the release of the alarm-box magnet BM . The extra impulse there- 50 after sent out from the section relays SR_{1a} , SR_{1b} etc. to the alarm-box magnet BM increase the likelihood that said magnet will actually be released.

The plant according to the invention may also 55 in known manner be provided with relays for indicating earthing of the loop conductors.

Certain modifications may be made in the described arrangements without departing from the spirit of the invention. The resistance M_a may, 60 for instance, be entirely dispensed with or substituted by a relay having a low resistance which relay is energized upon a short-circuit and is provided with a separate short-circuit indicating device, by way of example an optical device. The 65 relay R_b is then made with a higher resistance so that it does not drop its armature upon a short circuit occurring.

Further, the simple control relays R_a and R_b may each be substituted by two or more series-connected relays in order to increase the safety of operation, as in this case at least any of the series-connected relays must drop its armature upon an interruption occurring in the loop conductors. The short-circuiting contact K_4 of the 70 control relay R_b shown in Figures 1 and 2 may

also be adapted to short-circuit the resistance M_b as well as the own winding of the relay when the relay drops its armature in order to reduce the resistance in the circuits for the section relays and, if desired, for the fault relays in case said 5 relays are connected in series with the section relays (compare Figure 1).

The series-connected normally open contacts k_1 and k_2 of the control relays R_a and R_b may be substituted by parallel-connected normally 10 closed contacts for opening the circuit of a special alarm relay controlled by closed circuit current which relay in turn, upon a simultaneous opening of said two parallel contacts, closes the circuit through the alarm-box magnet BM in order to 15 release the same. Also the remaining normally open contacts may in similar manner be exchanged against normally closed contacts for closed circuit currents without considerably altering the rest of the plant. 20

In very large systems having several sections the embodiment shown in Figure 2 has the inconvenience that it is difficult to obtain fault relays FR_a and FR_b having a sufficiently large number of contacts k_{1a} , k_{11a} etc. This difficulty may be 25 eliminated by connecting several fault relays in parallel or by providing each section relay SR_{1a} , SR_{11a} etc. with an extra contact closing the interruption k_{1a} , k_{11a} etc. in the next following section. The fault relay, by way of example FR_a , 30 then only has to close the circuit for the first section relay SR_{1a} which then closes the circuit for the other section relay SR_{11a} etc.

It will be understood that in automatic fire alarm systems ordinary switches, isolating 35 switches, etc. for the supervision of the system may be provided.

I claim:—

1. In an automatic fire alarm system, a protective circuit including a plurality of loops each 40 made up of two adjacent parallelly extending conductors, the corresponding conductors of all loops being connected in series so as to form two circuit branches connected in parallel to a common source of current, thermostatic circuit breakers inserted in both conductors of each loop, a first electromagnet coil in one of said circuit branches, a second electromagnet coil in the other of said branches, an alarm, contact means and connections controlled by said electro-magnet 45 coils, jointly, for closing a circuit through the alarm on the de-energization of both conductors, indicating means individual to each loop including two windings, each normally short-circuited by one loop conductor, an indicator for each loop 50 and connections and contact means controlled by said windings to close a circuit through a corresponding indicator, on a break in any loop. 55

2. An automatic fire alarm system as claimed in claim 1, in which the two electromagnet coils are 60 arranged in common to all loops.

3. In an automatic fire alarm system, a protective circuit including a plurality of loops each made up of two adjacent parallelly extending conductors, the corresponding conductors of all 65 loops being connected in series so as to form two circuit branches connected in parallel to a common source of current, thermostatic circuit breakers inserted in both conductors of each loop, two relays allotted to each loop, a winding on each relay normally short-circuited by the corresponding loop conductor, an alarm contact means and connections controlled by said relays jointly 70 for closing a circuit through the alarm on a break in the loop, an indicator for each loop, and 75

connections and contact means controlled by said relays to close a circuit through a corresponding indicator on a break in any loop.

5. In an automatic fire alarm system, a protective circuit including a plurality of loops each made up of two adjacent parallelly extending conductors, the corresponding conductors of all loops being connected in series so as to form two circuit branches connected in parallel to a 10 common source of current, thermostatic circuit breakers inserted in both conductors of each loop, a first electromagnet coil inserted in one circuit branch at the positive pole of the current source, a resistance inserted in the same circuit branch, 15 at the negative pole of the current source, a

second electromagnet coil inserted in the other circuit branch at the negative pole of the current source, another resistance inserted in the circuit branch last mentioned at the positive pole of the current source, an alarm, contact means and connections controlled by said electromagnet coils jointly for closing a circuit through the alarm on the de-energization of both conductors, indicating means individual to each loop including two windings, each normally shortcircuited by one 10 loop conductor, an indicator for each loop and connections and contact means controlled by said windings to close a circuit through a corresponding indicator on a break in any loop.

OLOF INGEMAR HARALD EKMAN. 15
